UNITED STATES PATENT OFFICE.

GEORGE H. BAKER, OF IDAHO FALLS, IDAHO

LAMP.

1,127,577.

Specification of Letters Patent.

Patented Feb. 9, 1915.

Application filed August 10, 1910. Serial No. 576,422.

To all whom it may concern:

Be it known that I, GEORGE H. BAKER, a citizen of the United States, residing at Idaho Falls, in the county of Bingham and State of Idaho, have invented new and useful Improvements in Lamps, of which the following is a specification.

This invention relates to lamps and more particularly to the rear lamps of automobiles.

The object of the invention is to provide a simple and efficient lamp of this character which will carry the number of the machine and will show the same on either side of the machine at all times.

A further object of the invention is the provision of a cheaply constructed, rear lamp for automobiles which will exhibit the number at each side of the machine and which will present a red light or danger signal at the rear of the machine.

Further objects of the invention will appear as the following specific description is read in connection with the accompanying drawing which forms a part of this application, and in which:

Figure 1 is a front elevation. Fig. 2 is a horizontal section taken on the line 2—2 of Fig. 1.

Referring more particularly to the drawing 1 represents the back plate upon which there is mounted any suitable attaching device, 2 the top plate and 3 the bottom plate of the lamp casing. The top and bottom plates are preferably substantially trapezoidal in horizontal cross section and have the side plates 4 secured thereto and to the front plate 5. The side plates are preferably made of transparent glass and the front plate is apertured to receive a red glass 6. Positioned immediately behind the glass plates 4 is an opaque shield 7 in which is cut the figures 8 representing the number of the machine so that the light from the burner 9 will pass therethrough when the lamp is lighted at night and the figures will show white in the day time.

Positioned immediately behind the burner

9 and secured to the back plate 1 is a substantially V-shaped reflector 10 which is adapted to throw the rays from the light through the side plates 4, a sufficient amount of light passing through the red glass 6 so as to produce a danger signal and prevent rear end collision. The burner and reflector 10 may be of any suitable type, material or size, the principal feature of the invention being the trapezoidal casing with the transparent side plates having the opaque number shield arranged behind them and with the colored or semi-opaque bull's-eye or danger light at the apex of the casing.

Having thus described the invention, what is claimed is—

1. A lamp of the class described comprising a casing substantially trapezoidal in horizontal cross section, the inclined side walls of the casing being opaque and provided with indicia-defining openings therein for the passage of light therethrough, a source of light disposed medially within the casing, and a reflector disposed within the casing adjacent to the wider base wall of the same, the said reflector including angularly disposed faces converging as they diverge from the said wall.

2. A lamp of the class described comprising a casing substantially trapezoidal in horizontal cross section, the inclined side walls of the casing being opaque and provided with indicia-defining openings therein for the passage of light therethrough, a source of light disposed medially within the casing, and a reflector disposed within the casing adjacent to the wider base wall of the same, the said reflector including angularly disposed faces converging as they diverge from the said wall, each outer, reflecting face of the reflector being horizontally concave.

In testimony whereof I affix my signature in presence of two witnesses.

GEORGE H. BAKER.
